UNITED STATES PATENT OFFICE.

HIRAM C. HAWLEY, OF VALLEY FALLS, AND JAMES I. DAVIS, OF TOPEKA,
KANSAS.

DEVICE FOR LOADING CATTLE ON RAILWAY-CARS.

SPECIFICATION forming part of Letters Patent No. 274,192, dated March 20, 1883.

Application filed January 30, 1883. (No model.)

To all whom it may concern:

Be it known that we, HIRAM C. HAWLEY, of Valley Falls, Jefferson county, and JAMES IRA DAVIS, of Topeka, Shawnee county, and 5 State of Kansas, have invented certain new and useful Improvements in Devices for Loading Cattle on Railway-Cars; and we do hereby declare that the following is a full, clear, and exact description of the invention, which will 10 enable others skilled in the art to which it appertains to make and use the same, reference being had to the accompanying drawings, which form a part of this specification, and in which—

15 Figure 1 is a side view of our stock-loading chute. Fig. 2 is a detail view of the end of the windlass and means for operating it, and Fig. 3 is a detail view of the upper part of the platform-railing and the sliding cage.

20 Similar letters of reference indicate corresponding parts in all the figures.

Our invention has relation to chutes for loading cattle on stock-cars; and it consists in the improved construction and combination of 25 parts of the same, as hereinafter more fully described and claimed.

In the accompanying drawings, the letter A indicates the inclined plane of the chute, leading up to the platform B, which former is 30 provided with rails C on the sides, and cross-strips D to present better foothold for the cattle. The platform consists of two longitudinal timbers, E, resting and fastened upon cross-pieces F between the supporting posts, in 35 which timbers are journaled four or more friction-rollers, G.

H is a sliding cage or bridge, which is provided at its bottom with two longitudinal metallic rails, I, which slide upon the rollers G, 40 and is provided at its sides with rails J, the top ones, K, of which are provided upon their edges with rollers L, which roll upon the under side of two metallic ways, M, extending longitudinally between the top of the posts N, 45 which support the platform and its side rails.

By having the cage rolling upon the friction-rollers G and providing it at its top with the rollers L, rolling against the ways M, the cage may be extended with comparatively little la-

bor, and the upper ways will prevent the end 50 of the cage from tilting downward if the car-platform is lower than the chute. The cage is operated by means of a windlass, O, journaled under the platform in bearing P, to which four or more or less ropes or chains, Q, are 55 fastened, the ends of which are fastened to the under side of the bottom of the cage, two at each end, so that the cage is extended or drawn back by turning the windlass in opposite directions. The windlass may be turned 60 by a crank, R, upon its shaft, or it may be turned by a person standing on the chute by means of a vertical shaft, S, journaled in bearings in the side rails of the platform, and having a hand-wheel, T, upon its upper end. The 65 lower end of this shaft is provided with a bevelled pinion, U, which engages a similar pinion, V, upon the shaft of the windlass. This pinion U slides upon the vertical shaft S, while it is made to turn with it by a feather, 70 W, upon the shaft fitting into an inner groove, X, in the pinion. The upper side of the pinion is provided with a flanged neck, Y, in the groove of which a bifurcated lever, Z, extends, by means of which the pinion may be 75 thrown out of gear when the crank is to be used, while by dropping the pinion into gear the cage may be operated by the hand-wheel.

Having thus described our invention, we claim and desire to secure by Letters Patent 80 of the United States—

1. In a stock-loading chute, the platform having bottom rollers, G, and top ways, M, in combination with the cage having bottom rails, I, and upper rollers, L, and means for 85 operating it, as and for the purpose shown and set forth.

2. The combination of the sliding cage H, having ropes or chains Q, fastened at both ends of its bottom, with the windlass O, having crank R and pinion V, and the vertical shaft S, having sliding pinion U, adapted to engage pinion V, as and for the purpose shown and set forth.

3. The herein-described stock-loading chute, 95 consisting of the platform B, having inclined plane A, bottom rollers, G, and top ways, M, cage H, having bottom rails, I, top rollers, L,

and chains or ropes Q, windlass O, having crank R and pinion V, and vertical shaft S, having pinion U and means for engaging and disengaging it, all constructed and combined substantially as and for the purpose shown 5 and set forth.

In testimony that we claim the foregoing as

our own we have hereunto affixed our signatures in presence of two witnesses.

HIRAM CLARK HAWLEY.

JAMES IRA DAVIS.
